UNITED STATES PATENT OFFICE

FRANK J. WERNER, OF PORTAGE TOWNSHIP, PORTER COUNTY, INDIANA

FUEL BURNER NOZZLE

Application filed August 30, 1927. Serial No. 216,489.

My invention relates to improvements in fuel burner nozzles, and it more especially consists of the features pointed out in the claims.

5 The purpose of my invention is to provide a fuel burner nozzle having a plurality of concentric delivery passages adapted to deliver inflammable fuels through such passages in uniform cylindrical layers; that positively and rigidly maintains the concentric relation of the delivery passages against change under variable conditions of expansion or contraction; that by reason of the accurate maintenance of the uniform concentric cross section of the delivery openings produces uniform combustion throughout the 360 degrees of the openings; that by reason of the concentric relation of the openings prevents the distortion of the burner parts, 15 such distortion inevitably occurs when the delivery openings form a non-concentric exit zone, a condition that subjects the burner parts immediately adjacent the exits to dissimilar expansions or contractions thus accentuating the uneven distribution of the burner flame; that provides means for adjusting the size of the final burner opening; and that retains a uniform cross section of each of the three passage or delivery outlets. 20

With these and other ends in view, I illustrate in the accompanying drawings such instances of adaptation as will disclose the broad underlying features of my invention without limiting myself to the specific details shown thereon and described herein.

Figure 1 is a side elevation in section showing parts broken away.

Fig. 2 is a top plan view of Fig. 1, partly in section.

Fig. 3 is a front elevation in section on line 3-3 of Fig. 1.

Fig. 4 is sectional elevation similar to Fig. 1 showing positive centering means located immediately at the outlets, leaving concentric chambers back of these outlets.

Fig. 5 is a sectional view, similar to Fig. 4 but with the central tube removed.

Fig. 6 is a modification of the form of the central tube.

In adapting my invention to the different conditions of actual practice, I may use whatever alternatives of construction that the exigencies of such conditions may demand without departing from the broad spirit of my invention, which in its relation to the use of different kinds of fuels in the same burner is illustrated and described in my co-pending application, Serial No. 717,034, filed May 31, 1924, which has matured into Patent #1,783,818, on December 2, 1930.

The failure of fuel burners, especially of the high capacity type as found in actual practice prior to my invention, is fundamentally due to the fact that there has been no provision for maintaining a true concentric relation between the different parts of the burner nozzle that define the exit passages, which feature forms a part of my invention above referred to.

The burner nozzle in the main consists of a central tube 1. This tube has a threaded rear end 2 on which the inlet pipe 33 is threaded. It has an enlarged diameter shoulder 4 in which spanner openings 45 are formed. About midway its length it is threaded externally at 3 to receive the threaded portion of the rear wall 9. From the threaded portion 3 forward a reduced diameter 5 is formed which serves to absolutely center and hold the adjacent parts in permanent concentric relation. At the front end of the portion 5 the tube is reduced in diameter at 6, which portion terminates in a beveled front end 7. A bushing 8 having a reversed conical restricted opening 40 may be placed in the front end of the tube 1, as needed.

The rear nozzle wall 9 has an external threaded portion 10 on which the nozzle cap 11 is threaded and a concentric tubular forward extension 46 which connects the rear wall 9 with a central partition 12. This wall continues forward in a gradually reducing diameter indicated by 15. Outside of the wall 46 an annular chamber 13 is formed and inside of this wall an annular chamber 14 is formed. The chamber 13 is bounded by the walls 9, 46, partition 12, and cap 11, while the inner chamber 14 is bounded by the walls 9 and 46, the partition 12 and the tube 1. A

series of openings 18 lead from the chamber 13 to curved external chambers 17, and openings 19 lead from the chamber 14 to internal curved chambers 16.

- 5 5 In order that the annular outlet 24 from the chambers 16 and the annular outlet 23 from the chambers 17 may be held in permanent concentric relation to each other and the tube 1, internal ribs 21 extend from the curv-
10 ing wall 15 in a radial direction into close contact with the portion 5, as instance at 42, against the tube 1. To also maintain the concentric relation of the outlet 22 of the cap 11, the cap engages the outside diameter of the partition 12 and is supported between the partition 12 and the outlet 22 by means of ribs 20 extending radially outward from the curved wall 15 into close engagement with the inner surface of the cap 11, as instance at 41. Advantageous results are secured by making the cross sectional area of the annular outlets 23, 24 and 25 substantially the same, but the broad feature of my invention resides in the permanent maintenance of the concentric relation of the burner outlets.

A rear casing 26 passes over the unthreaded portion 35 of the nozzle wall 9. It has a central opening 47 engaged by the shoulder 4 of the tube 1. The inlet tube 33 is also found in this opening. Diametrically oppositely positioned openings 27 serve inlet tubes 28 and 29 respectively. The tube 28 is threaded into the nozzle wall 9 and it communicates with the inner chamber 14 through openings 30; and the tube 29 is similarly threaded into the nozzle wall 9, it, however, leads into chamber 13 through openings 31. A locking ring 34 on the tube 33 serves to hold the casing 26 assembled against the nozzle wall 9. A locking ring 32 threaded onto the portion 3 of the tube 1 serves to hold the delivery end of the tube 1 in a predetermined relation to the exits 22, 23 and 24.

Spanner openings 43 in the cap 11, 44 in locking ring 32, 45 in enlargement 4, and similar openings in the locking ring 34 serve the usual purpose of these expedients in facilitating the assembly of the different parts of the burner. The rear portion of the nozzle wall 9 is recessed at 36 on each side, as shown in Figs. 2 and 3, to form abutting faces which serve to hold the nozzle by means of a wrench, or otherwise, while the cap 11 is threaded onto the portion 10 as far as the engaging faces 41 of the external ribs 20 will permit.

It will be seen from Figs. 4 and 5 that the means for holding the openings 23, 24 and 25 in a fixed spaced-apart relation may be placed at the front of the chambers 16 and 17. By shortening the ribs 20 and 21 as shown in Figs. 4 and 5 or rather omitting them adjacent the wall 12 there is formed an annular chamber 51 between the nozzle walls 11 and 15 and an inner annular cham-

ber 52 between the curving wall 15 and the inner tube 5. This is accomplished by forming short radial projections 48 on the inside of the wall 15 which terminate in contact with the tube portion 6 of the tube 5, or the portion 50 of the modified tube shown in Fig. 6. This relation of parts positively holds the opening 25 concentric with the tube.

The outer nozzle shell 11 is similarly provided with short radial projections 49 which terminate against the curving wall 15. This positively holds the opening 22 concentric with the tube and at the same time holds the opening 23 between the ends of walls 11 and 15 in definite spaced apart unobstructed concentric relation, so that the annular openings 22 and 25 and the lateral opening 23 are always in the same operative relation. The inner ends of the projections 48 are bored out to the diameter of the tube 5 which fits snugly against them and the inside of the projections 49 are made to conform to the outer surface of the curving wall 15. If desired the projections 49 may be formed on the wall 15 and their outer edges made to conform and engage the inner surface of the shell 11. The exact form of the projections 48 and 49, as shown, is not material; the only element of importance is that rigidly engaging means be used to hold the openings 22, 23 and 25 in unvarying spaced apart relation.

What I claim is:

1. A fuel burner adapted to utilize different fuels, said burner comprising a plurality of inlet tubes, an internal centering tube, an intermediate cylindrical dividing wall, an external cap having a central opening, external ribs from the dividing wall to the cap; internal ribs from said wall to the tube, the tube, the division wall and cap being in spaced apart relation to form exit openings therebetween; and means for delivering a combustion maintaining supply between the dividing wall and the cap, the dividing wall and the tube, and independently thereof through the interior of the tube.

2. A fuel burner comprising a central tube, a nozzle member spaced apart from the tube, an external cap spaced apart from the nozzle member, and means for positively holding the parts in rigidly concentric relation in contact with each other immediately at their exit.

3. A fuel burner comprising an inner tube, a nozzle member held concentrically on the tube, a cap held concentrically on the nozzle member, and a mid-dividing wall of the nozzle member terminating in an internal exit opening between the dividing wall and the tube and an external exit between the dividing wall and the cap, and means for positively maintaining the parts in relatively

- permanent concentric and lineal spaced apart relation immediately at their outlet.
4. In fuel burners, an internal tube, an external cap having an opening of slightly larger diameter than the adjacent external diameter of the tube, a nozzle member positioned between the cap and the tube, a cylindrical dividing wall of the nozzle member terminating in a delivery opening slightly larger than the adjacent external diameter of the tube, internal projections from the dividing wall to the tube, external projections from the dividing wall to the cap said projections serving to positively position the parts in concentric relation with each other immediately at their outlet, and means for holding them in assembled relation.
5. In multiple purpose fuel burners, an inner tube, a nozzle member supported by the tube, an external cap having a reduced size opening at its front end supported by the nozzle member, a dividing wall of the nozzle member between the cap and the tube forming a plurality of chambers therebetween, integral means projecting from the dividing wall internally into engagement with the tube and externally into engagement with the cap adapted to position the parts in contact with each other in concentric relation, and means adjacent the end of the dividing wall and nozzle member for positively holding these parts assembled on the tube in a fixed spaced-apart relation immediately at their outlet.
6. In fuel burners, a central tube having a reduced diameter exterior at its front end, a nozzle surrounding the tube forming an interior chamber having an opening adjacent the reduced exterior diameter of the tube, an external cap surrounding the nozzle forming an exterior chamber also opening adjacent the end of the tube, and means for concentrically holding the nozzle spaced apart from the tube and the cap spaced apart from the nozzle.
7. In fuel burners, a central tube, a nozzle surrounding the tube forming a partition wall between interior and exterior chambers having openings adjacent the exterior surface of the tube near its front end, an external cap surrounding the nozzle, the outer chamber, and the tube, said cap having a central opening adjacent the tube end, and means for concentrically holding the nozzle spaced apart from the tube and the cap spaced apart from the nozzle and tube.

In testimony whereof I affix my signature.
FRANK J. WERNER.
